TRANSPOSED LEAD-IN

Fred E. Johnston, Cincinnati, Ohio, assignor to
 The Crosley Radio Corporation, Cincinnati,
 Ohio, a corporation of Ohio

Application July 26, 1935, Serial No. 33,370

9 Claims. (Cl. 173—81)

The transposed lead-in for antenna systems, comprising a pair of conductors the positions of which are periodically reversed as respects a given plane, has come into considerable popular favor. It has been customary in the past to provide a ceramic or moulded block or plate with means such as holes or slots for engaging the wires when the antenna is installed. It has thus been necessary for the person doing the installation work to attach these blocks or engage the wires in the slots therein every few feet to accomplish the necessary transposition. This becomes a tedious and laborious job because the antenna must be hoisted a few feet at a time while the blocks are attached. Moreover there is some danger of the blocks becoming disengaged during installation, and until the lead-in is finally stretched in place, thus requiring a repetition of the operations.

The art has offered the alternative suggestion of systems embodying fundamentally a pair of twisted insulated wires. Tests demonstrate that the average impedance of a lead-in of twisted wires is in the region of 100 ohms, which makes such a lead-in unsuitable for direct connection to most types of antenna and receiver. In addition the dielectric losses existing in a twisted pair lead-in are bound to effect its performance; and such a lead-in requires the use of an impedance matching transformer, in which also there are serious losses. The transposition block lead-in, on the other hand, has an impedance averaging about 500 ohms, which is a value very much more suitable for use with the ordinary radio set. It is an object of my invention to provide a lead-in and a structure which has the advantages of the transposition block type, but not its disadvantages. It is a further object of my invention to provide a means for the construction of such a lead-in which is permanent in its character, and which permits the manufacture, use and sale of such a lead-in as a stock item already constructed, and sold in bulk, or any such lengths as may be required for a particular installation.

These and other objects of my invention which will be set forth hereinafter, or will be apparent to one skilled in the art upon reading these specifications, I accomplish by that particular construction and arrangement of parts and in that article of which I shall now describe an exemplary embodiment. For clearness reference is made now to the drawing:

Figure 1 is a face view of one of my assembling means complete.

Fig. 2 is a side elevation thereof.

Fig. 3 is a face view of one of the component parts of the device, with the insulated conductors in place.

Fig. 4 is a sectional view taken along the lines 5 4, 4 of Fig. 1.

Fig. 5 is a plan view of a length of completely constructed lead-in.

Briefly, in the practice of my invention, I provide means for positively clamping a pair of wires 10 in crossing relationship in such a way that they cannot become disengaged. The means also is adapted to gauge the distance of the wires one from another in the longitudinally disposed portions of the lead-in. The device is of such character that it can be installed in the field if desired, and when so installed obviates the difficulties hitherto encountered in the accidental disengagement or release of the wires from the blocks. The device, however, is particularly important in that it permits the manufacturing of lead-in constructions of indefinite length, and the convenient shipment and sale thereof as completed articles of commerce.

In the practice of my invention, I preferably 25 provide a pair of formed or moulded plates for each cross-over of the insulated conductors in the lead-in. These plates are identical, and the outer and inner configurations of an exemplary form thereof preferred by me will be appreciated 30 from a consideration of Figs. 1 and 3. In these figures, I have shown the blocks (which may be of ceramic material, but are preferably made by known moulding procedures from Bakelite, or other synthetic resinous compositions) in the 35 form of plate-like members having a body 1. The inner face of the body is flat, as shown at 1a in Fig. 3. There is a central and preferably circular protuberance 2 on the outside of the plate allowing for a corresponding recession 2a on the 40 under side of the plate. Ribs 3 on the outside of the plate connect the protuberances with the four corners, and beneath these ribs there are corresponding depressions 3a on the inside of the plate to receive the wires. The corners of 45 the plate are preferably beveled as at 5, and the plate may be strengthened by an exterior peripheral rib 6. Additional strengthening ribs 7 may connect the peripheral rib with the raised portion 2, and intermediate the length of these 50 ribs I provide enlarged portions 1a surrounding perforations through which fastening means may be passed. In use, the wires 8 are crossed, as indicated in Figs. 3 and 4, and two of the plates in opposed relationship are placed over the wires 55

55

where they cross. The plates are then fastened together by suitable fastening means extending through the perforations aforesaid. If the lead-in is to be manufactured as a stock article, it is 5 most convenient and economical to use some such fastening means as eyelets or grommets of known type. If the lead-in is to be assembled in the field, it will be necessary to use some type of separable fastening, for which purpose a bolt 10 and nut will serve.

The disposition and use of my device will be clear from the several figures. Essentially I have achieved a structure which is permanent, especially in the sense that the wires are firmly 15 clamped therein, and are not liable to displacement. Thus in the practice of my invention I am enabled to take indefinite lengths of conductors, attach my plates to them with the suitable transposition of the conductors at the desired intervals, and in this way make indefinite lengths of 20 preformed lead-in structure, which can be conveniently rolled up on a reel, or on a card or board, or otherwise packaged for shipment and storage. No difficulty is had with the tangling of 25 the wires because these wires are firmly held in the transposition plates and cannot become disengaged therefrom, as would be the case with the ordinary transposition blocks of commerce.

In Fig. 5, I have indicated the transposition 30 members broadly at 9, the wires again being shown at 8. This figure shows the appearance of a length of my preformed lead-in structure.

Modifications may be made in my invention without departing from the spirit thereof.

Having thus described my invention, what I 35 claim as new and desire to secure by Letters Patent, is—

1. In a transposed lead-in structure comprising a pair of conductors parallel throughout a major 40 portion of their length, but transposed at intervals, a pair of permanently attached plates at the transposition points having grooves whose axes cross within the boundaries of the plates, for effecting the transposition and for gauging the 45 interspacing of said conductors in their parallel portions.

2. In a transposed lead-in structure comprising a pair of conductors parallel throughout a major portion of their length, but transposed at intervals, permanently attached means at the transposition points for effecting the transposition and for gauging the interspacing of said conductors in their parallel portions, said means comprising a pair of plates in opposed relationship, one on 55 either side of said conductors, said plates having grooves whose axes cross within the boundaries of the plates, and means for fastening said plates together so as to cause said plates to clamp said conductors.

3. In a transposed lead-in structure comprising a pair of conductors parallel throughout a major portion of their length, but transposed at intervals, permanently attached means at the transposition points for effecting the transposition and for gauging the interspacing of said conductors in their parallel portions, said means comprising a pair of plates in opposed relationship, one on either side of said conductors, means for fastening 65 said plates together so as to cause said plates to clamp said conductors; said plates having upon their opposed sides grooves to receive said con-

ductors and hollowed-out portions permitting the crossing of said conductors.

4. As an article of commerce, a preferred lead-in structure of indefinite length comprising a pair of conductors parallel throughout the greater 5 portion of their length and crossing at intervals, and a pair of permanently attached opposed plates fastening said conductors together at said crossing points, said plates having grooves whose axes cross within the boundaries of the plates so 10 as to receive said wires between them and to gauge the interspacing of said wires in their said parallel portions.

5. A transposed lead-in member comprising a substantially square plate of suitable material, 15 said plate having a substantially plane side, with grooves in said side for receiving wires to be placed in transposed relationship, and a depression deeper than said grooves for permitting crossing 20 of said wires.

6. A transposed lead-in member comprising a substantially square plate of suitable material, said plate having a substantially plane side, with grooves in said side for receiving wires to be placed in transposed relationship, a depression 25 deeper than said grooves for permitting crossing of said wires, said plate on the opposite side having corresponding ridges and a protuberance, and provided with perforations whereby a pair of 30 said plates may be fastened together in opposed relationship to clamp the said conductors therebetween.

7. A transposed lead-in member comprising a substantially square plate of suitable material, said plate having a substantially plane side, with 35 grooves in said side for receiving wires to be placed in transposed relationship, a depression deeper than said grooves for permitting crossing of said wires, said plate on the opposite side having corresponding ridges and a protuberance, and 40 provided with perforations whereby a pair of said plates may be fastened together in opposed relationship to clamp the said conductors therebetween, said plate having a peripheral strengthening rib.

8. A transposed lead-in member comprising a substantially square plate of suitable material, said plate having a substantially plane side, with 45 grooves in said side for receiving wires to be placed in transposed relationship, a depression deeper than said grooves for permitting crossing of said wires, said plate on the opposite side having corresponding ridges and a protuberance, provided with perforations whereby a pair of 50 said plates may be fastened together in opposed relationship to clamp the said conductors therebetween, said plate having a peripheral strengthening rib, and additional ribs disposed radially of said protuberance, the corners of said plate being beveled.

9. A pre-constructed, transposed lead-in comprising a pair of conductors and transposing means, said conductors extending parallel to each other between said transposing means, and crossing each other at said transposing means, said 65 transposing means comprising a pair of opposed, grooved plates engaging said conductors, and means to hold said plates in clamping relationship with said wires whereby the position of said plates on said wires is fixed.

FRED E. JOHNSTON.
